INVENTOR,
Anthony Clocchock
BY *Abraham Horst*
ATTORNEYS.

UNITED STATES PATENT OFFICE.

ANTHONY PLOCHOCKI, OF BROOKLYN, NEW YORK, ASSIGNOR OF ONE-HALF TO
EDWARD BRZOZOWSKI, OF BROOKLYN, NEW YORK.

GAME DEVICE.

Application filed July 11, 1921. Serial No. 483,829.

To all whom it may concern:

Be it known that ANTHONY PLOCHOCKI, a citizen of the United States, and resident of Brooklyn, in the county of Kings and 5 State of New York, have invented certain new and useful Improvements in Game Devices, of which the following is a specification.

This invention relates to foldable bowl- 10 ing games and has for an object the provision of a complete portable bowling table, together with suitable ball handling devices and targets, all of which parts may be readily taken apart and collapsed into a 15 compact unit.

In the drawings illustrating the preferred form of my invention, Fig. 1 is a plan view of my improved device in the operative position thereof. Fig. 2 is a front elevation of the 20 same. Fig. 3 is a side elevation of the same. Fig. 4 is a plan view of the device as it appears in its folded or collapsed position, and Fig. 5 is a front elevation of the same.

25 The game when put to use lends itself to a multiple of applications quite obvious to the contestants participating. Referring to the drawings, the active contestants standing at A, rolls a series of balls one at a time 30 upon the smooth, level alley 1, in the direction indicated as B, retaining walls 2 preventing misdirected balls from falling off the alley 1. Across the path of the balls, a row of targets 3 are suspended by their 35 hinged ends 4 upon hinge pin 5. Hinge pin 5 is held in the opening of the eyes 22 and 23 at the upper ends of posts 6 and 7. The lower extremity of targets 3 are reduced in width so as to provide a gap between adja- 40 cent targets somewhat larger than the diameter of the balls used. A ball in its passage down the alley 1 may or may not strike one of the targets presented to its path, depend- 45 ing upon the accuracy with which it was directed.

When a ball strikes a target, that target is set into oscillating motion, large numbers C, identify the particular target struck.

50 Thus when a given number of balls are used, as described above, by each of a number of a number of contestants, the points made are recorded, that is the addition of the numbers C upon those targets set into motion by each contestant is recorded in his favor, thus

a basis is had for an intensely interesting 55 competitive form of game.

One of the features of this game is the automatic return of the balls to the contestants position A. This is accomplished by means of the cupped shaped bottom 9, at the rear end of the alley 1, the balls when entering this position of the device are caused to roll toward hole 10, at the apex of the conical wall of cup 9, the ball dropping into opening 10 enters conduits 11 and 14 connect- 60 ed to opening 10. Due to the downward slope of conduits 11 and 14, the ball rolls downward into pocket 12, at the end of conduit 14. The upper side of the conduit is 65 open, so that the ball is under observation at 70 all times.

Another feature of this device is the means employed for collapsing or folding the game when not in use, thereby a game of large dimensions may be reduced to portable size, 75 and also lend itself conveniently for storing purposes, this is accomplished in the following manner;

Conduits 11 and 14 are made of two de- 80 tachable members joined at 13, 11 telescoping into 14.

The supporting legs 15 and 16 are fastened to the under surface 17 of the wall or alley 1 with hinges 30, the open position of these legs being maintained with the aid of flat 85 springs 18 fastened to legs 15 and 16, and resting in notches 19 of the surface 17. When the legs 15 and 16 are pressed inward, the spring 18 snaps past the notch 19 permitting the legs 15 and 16, to freely swing closed 90 upon their respective hinges 30.

The body of game can then be folded in two by means of the hinge 20.

The target 3 and its carrying posts 6 and 7 are detachably held in holes 21, 22 and 23 95 are two screw eyes made to fit posts 6 and 7 permitting the latter to lie flat against the underside 17 of alley way 1.

The receiving pocket 12 can be lifted out of its operative position in which the extensions 12' engage the spring hook 24 by an upward sliding motion. This pocket 12 fits with its flat side 25 against the underside of alley way 3 and is held there by the engagement of screw 26 with the keyhole opening 27 in side 25 of pocket 12, in the collapsed position of my improved device. It will be 100 seen that a complete bowling alley is pro- 105

vided, in which the various parts, though firmly held in their respective operative positions when in use, may be quickly and readily detached for collapsing the device.

5 I claim:

1. In a collapsible game device of the character described, a foldable table having an opening in the rear end thereof, side rails for said table having transverse holes therein, a 10 row of swingable targets adapted to be set in motion when struck by a playing ball, an upright adapted to be removably inserted in the holes in said rails, an eye at the upper end of each of said posts, a shaft 15 passing through said eye, and carrying said targets, means operatively connected to said table near the opening thereof for guiding the playing ball back to the player, and detachable means near the players end of said 20 table for receiving said ball.
2. In a collapsible game device of the character described, a foldable table, a row of targets adapted to be set in motion when struck by a playing ball, an upright removably inserted in said table, a shaft carried by 25 said upright and passing through said targets, an eye secured to the under side of said table for supporting said targets in the folded position of said game device, a 30 turned ball receptacle comprising a box portion open at the top thereof and exten-

sions from the rear side of said box, foldable legs hinged to said table, spring members secured to said legs and partly spaced from said legs for receiving and holding said extensions in the operative position of said receptacle, and a screw secured to the under side of said table for supporting said returned ball receptacle in the detached position thereof.

3. In a collapsible bowling alley and game, a table having short grooves on the under side thereof and an opening at the rear end thereof, a hinge on the middle of the under side of said table about which said table is foldable, legs hinged to said table near the ends thereof, springs secured to said legs and arranged to enter said grooves for normally maintaining said legs in their extended positions, oscillatory targets 45 50 55 removably mounted on said table, collapsible means for guiding the playing ball to the players end of said table, and detachable means adapted to be carried on the under side of said table in the detached position thereof near the opening therein for receiving the returned ball.

ANTHONY PLOCHOCKI.
